UNITED STATES PATENT OFFICE.

HERBERT T. FOGG, OF EAST ORANGE, NEW JERSEY, ASSIGNOR TO NATIONAL BISCUIT COMPANY, OF NEW YORK, N. Y., A CORPORATION OF NEW JERSEY.

CONTAINER-CRATE.

1,303,873.

Specification of Letters Patent. Patented May 20, 1919.

Application filed September 7, 1916. Serial No. 118,794.

To all whom it may concern:

Be it known that I, HERBERT T. FOGG, a citizen of the United States, residing at East Orange, in the county of Essex and State of New Jersey, have invented new and useful Improvements in Container-Crates, of which the following is a specification.

This invention relates to improvements in crates or separators adapted for use in the packing of biscuits, crackers, and like articles of fragile character, in containers or caddies.

The particular type of crate or separator embodying the features of this invention is made of comparatively stiff card or fiber-board and comprising intersecting and interlocked members, arranged to provide a crate-like structure, adapted to be inserted into the carton or container and to receive and separate the several rows of biscuits or other contents as they are packed in superimposed layers. Each crate or separator is preferably designed to accommodate one layer of the goods, and so constructed to form a series of horizontally arranged compartments or units adapted to receive and separate the several rows of each layer, thereby preventing the lateral shifting and movement of the contents of each layer, which otherwise would lead to breakage and damaging of the goods, in the transportation or handling of the containers or cartons. The several crates and the layers contained therein are preferably separated by the use of partition sheets placed intermediate each of such layers, and thereby serving to support the several crate layers one upon the other.

The object sought to be accomplished in the manufacture of crates or separators is to reduce the cost of labor and material entering into the production of these articles, and of equal importance the production of a separator whose construction will facilitate packing of the goods in the cartons or containers, that is, by making it possible to place the crate partially assembled into the container, and to insert the remaining parts as the packing of the goods progresses. It is toward the attainment of these general objects that the features of the present invention are directed, as well as certain other

objects, which will hereinafter be pointed out.

The device embodying the features of my invention is clearly set forth in the description which follows, and fully illustrated in the accompanying drawings, in which—

Fig. 1 is a view in perspective of a single crate or separator embodying the features of the invention;

Fig. 2 is a view in elevation of the blank from which the body member is formed;

Fig. 3 is a view in elevation of a single cross or crate strip;

Fig. 4 is a view in perspective showing the manner in which the body member may be closed by the provision of overlapping flaps connected together;

Fig. 5 is a detail view in perspective showing the arrangement of the notches in the flaps shown in Fig. 4;

Fig. 6 is a modified form of the crate, with end wings folded in one position;

Fig. 7 is a perspective view of one of the members of Fig. 6, with the end wings folded in reverse position;

Fig. 8 is a view in elevation of the members of Fig. 6 in blank form;

Fig. 9 is a view of the end portion of a cross strip used with the members arranged as in Fig. 6; and

Fig. 10 is a view of the end portion of a cross strip used with the members arranged as in Fig. 7.

Referring now in a general way to the construction of a crate or separator embodying my invention, the same comprises a plurality of strips adapted to stand on edge and arranged in a series of parallel strips extending at right angles to each other, the strips of each series having interlocking connection with the strips of the other series by the provision of locking notches, thereby forming a crate of comparatively rigid and self supporting construction.

Although the preceding description is applicable to a general class of crates, the novel and improved features of construction embodying the present invention will now be described in detail.

The crate, consisting of intersecting strips

as before stated, comprises a body member 10 and a series of transverse or cross strips 11. The body member, as shown in the blank in Fig. 2, is a strip of sheet material having a width equal to the height of the completed crate and a length substantially three times the longitudinal dimension of a single strip. This strip is divided into three sections of substantially equal length. 10 to wit, two end sections 12, 12 and a central section 13, said portions being separated by suitable score lines, as will hereinafter be described. The end sections are identical in formation and are adapted to 15 be bent at right angles to and extend in the same direction from the central section 13, said end sections forming the two upright and parallel strips which extend at right angles to and engage the cross strips 11, 11, the adjacent ends being connected together by the central section 13, which extends parallel to the cross strips and, in fact, forms the outermost cross strip along one side of the crate. At the points 20 of connection or folding where the blank is bent to form the three sections, the following arrangements of cuts and score lines are provided: Extending from the upper longitudinal margin of the blank are perpendicular score lines 14, 14, which terminate midway between the upper and lower margins. Extending longitudinally from the inner ends of said score lines 14 and into the central section are two cuts 15, 15, each 25 of which joins at its outer end a cut 16, extending at right angles to each cut 15 and intersecting the lower longitudinal margin of the blank strip. The adjacent end portions of said cuts 15 and 16 are preferably 30 curved, in order to provide a rounded corner, for the tongue to be formed by said score lines and cuts, as will presently be pointed out. Upon bending the blank along the score lines 14, 14, so as to dispose the 35 end sections at right angles to the central section as shown in Fig. 1, the portions included between the edges of the cuts 15, 16 and the lower margin of the blank strip, form tongues 17, 17, which are integral 40 with the central section, and which extend outwardly from the ends of said end sections beyond and at right angles thereto, when the blank is folded into rectangular form. At each of the free ends of the end 45 sections is provided a similar arrangement of score lines and cuts, namely, a perpendicular score line 18, spaced a short distance inwardly from the end margins of the end section and extending parallel thereto from 50 the upper longitudinal margin thereof, to a point midway between the upper and lower longitudinal margins; a cut 19 extending longitudinally from the inner end of said score line 18 and in a direction away 55 from the free end margin of the section, and

a transverse cut 20 extending from the end of said longitudinal cut 19. This formation of score lines and cuts forms a wing or flap 21 at the free end of each end section, which is adapted to be bent inwardly along 70 the score line 18, as shown in Fig. 1, there being formed also a tongue 22, as before, which is integral with and remains in the plane of the wing 21, when the latter is folded, said tongue projecting outwardly 75 beyond the end sections of the strips, parallel with the tongues 17, 17, before described.

In addition to the parts already described, the blank is also provided with a 80 plurality of locking notches 23, arranged in equi-spaced relation throughout and along the upper margins of the end sections 12 of the strips and extending inwardly a distance substantially equal to one-half the 85 width of the strip. These notches are preferably V-shaped, having one edge perpendicular to said margin and complementary edge at an angle thereto. Although the particular shape of the notches is immaterial, 90 it may be pointed out that they are formed in the manner stated to avoid the difficulty which is experienced in cutting narrow notches in the material, of a width required to receive the thickness of the cross strips. 95

The remaining members of the complete crate are the cross strips 11 before mentioned. These strips (Fig. 3) are rectangular in shape and formed from a single thickness of the sheet material. In one of the 100 longitudinal margins of each strip are provided locking notches 24, preferably spaced inwardly from the ends of the strip and formed V-shaped as are the notches of the body member 10 and for the same reasons. 105

In assembling the several members of the crate it is to be understood that this operation is preferably carried on simultaneously with the packing of each layer; thus the first step is to insert within the container 110 the body member 10 (without the cross strips) with its parts folded as hereinbefore described, and in upright position, with its lower margins resting upon the bottom surface of the container or the partition sheet 115 of the layer immediately below. Inasmuch as the body member is not supported by the cross strips, as when the crate is completely assembled, it is the purpose, among others, of the wings and tongues to maintain the 120 body member in upright position, and in rectangular shape, prior to the addition of the cross strips. The purpose of the wings and tongues will be more clearly understood from the following: The body member is 125 proportioned to fit snugly within the container, and hence the ends of the tongues 17 and 22 at the ends of the sections 12, 12, will engage or abut against the walls of the container, and thus act to space said sections 130

away from said walls and maintain the same in parallel relation, as well as to prevent the shifting or movement of the body member within the container after the same has 5 been placed therein. Furthermore, the wings 21, 21, together with the tongues 22, 22 integral therewith, provide, in effect, transverse supporting members or feet which support the free ends of the body 10 member in upright position in the absence of the cross strips. The body member is further proportioned so that upon placing the body member within the container, the central section lies flatwise against the adjacent 15 wall of the container, as do the outer surfaces of the wings 21, 21 and the tongues 22, 22; thus the movement of the body member longitudinally of the end sections is prevented.

20 The body member having been placed within the container as described, the goods are packed in the form of rows, arranged transversely of the notched sections, there being added a cross strip after each row is 25 packed, until the entire layer is completed. It is manifest that, by reason of the construction of the body member, the same is retained in the proper upright position and rectangular form to permit the insertion 30 of the cross strips and the interlocking of the several notches of the body member therewith, without necessitating a subsequent shifting of the goods in order to restore the body member to a position or shape 35 to permit the cross strips to be properly inserted.

An obvious modification of the construction hereinbefore described is to increase the length of the wings or flaps at the free ends 40 of the end sections 12, 12, so that they may overlap and be joined together, thereby forming a body member that is closed on all four sides, instead of on three sides as described. This modification is shown in 45 Figs. 4 and 5, wherein the end sections 25, 25 are each provided with flaps 26, 26, which are considerably longer than the wings of the previously described form, said flaps being of a length sufficient to overlap at their 50 ends when folded into the same plane. Although any suitable means may be employed for connecting the overlapping end portion of these flaps together, one method consists in providing locking notches 27, 27, located 55 at the ends and on opposite margins of the flaps, which may be interlocked by inserting one notch 27 into the other, in the manner shown in Fig. 5.

The provision of the overlapping and 60 joined together flaps permits a more rigid construction, which enables the body member to retain its proper rectangular contour during the packing operation and before the cross strips are added.

65 In addition to the forms of crate already

described, it is desirable also to provide a 70 crate or separator that is adjustable to a certain degree, as regards the spacing of the parallel or end sections of the body member from the walls of the container. In order to secure a degree of adjustability, the following construction is resorted to, which departs from the forms already described only 75 in the details specifically referred to and shown in Figs. 6 to 10.

In this form of the device the body member comprises two identically formed sections 30, 30, which are disconnected from each other by the omission of the central section of the previous forms, and hence the 80 sections are free to be moved toward or away from each other. In addition to this feature, there are provided wings 31 and tongues 32 at each end of each section, said tongues and wings being formed in exactly the same 85 manner as described in connection with the wings and tongues of the end sections of the first form of crate described, namely, by providing score lines 33, 33, spaced inwardly 90 from each end of the section and extending from the upper longitudinal margin and inwardly a distance equal to approximately one-half of the section, longitudinal cuts 34, 34 extending from the inner ends of said score lines and in a direction away from the 95 end margins of the sections, and transverse cuts 35, 35 extending from the inner ends of said first mentioned cuts and intersecting the lower longitudinal margin. A specific 100 departure is made from the previous arrangement of the wings and tongues, which will be clearly set forth. In this instance the wings 31 are made of a different length than the tongues 32, that is, the distance measured longitudinally from the bend or 105 fold line 33 to the vertical or end margins of the wings is greater than the distance from the same fold line to the outer edge of the corresponding tongues. Thus, for instance, the length of the wings may be 110 one inch and the length of the tongues an inch and a quarter or an inch and a half, although, as it will be hereinafter seen, it is immaterial whether the wings or the tongues are of greater length. Now referring to Fig. 6, it will be seen that, if it is 115 desired to space the body sections an inch and a quarter or a half inwardly from the opposite walls of the container, the wings would be bent inwardly toward each other 120 and the tongues bent outwardly, and so act to determine the space separating the body sections and the wall, in the manner already described. Now, if it is desired to decrease 125 the space separating the body sections and the opposite walls of the container, it is only necessary to turn or bend the wings outwardly as shown in Fig. 7, instead of inwardly, said tongues being simultaneously bent inwardly, or, in other words, bend the 130

wings into the reverse position. Thus the wings now act in the same capacity as did the tongues, and, being shorter, serve to space the body sections a less distance from the walls of the container. It is obvious that different forms of crate strips 35, 36 must be used in connection with the two adjusted positions of the body sections, said strips differing only in the disposition of the locking notches with relation to the ends of the strip, that is, the notches 37 of a strip 35, used with the body sections as arranged in Fig. 7, must be spaced inwardly, say one inch, from the ends thereof, as shown in Fig. 9, and in the arrangement shown in Fig. 6 the notches 38 of a strip 36 would be spaced inwardly a correspondingly greater distance, say one inch and a quarter or a half, as shown in Fig. 10. In this manner then it is possible to provide a crate capable of at least two adjustments in the manner stated, by merely reversing the position or direction of folding the wings at the ends of the body sections and by providing cross strips with the corresponding arrangement of locking notches.

The crate strip embodying the features of my invention has the advantage of being constructed of the least amount of material necessary consistent with strength and rigidity, and, furthermore, contains the novel features which make it particularly useful and practical crate for use when the method of packing herein described is practised, namely, that of placing the crate within the container in partially assembled form and adding the cross strips as the rows of goods are successively completed.

The adjustable type of crate is of advantage in that it permits practically a single form of crate to be used for the packing of various kinds of goods which vary in thickness and hence require a certain variation in the spacing of the strips. This is accomplished in a simple manner, without necessitating the alteration of the crate, with the exception of the form of cross strip used.

The features embodying my invention may be variously modified without departing from the spirit of the invention, and for this reason it is not desired to limit the scope of the invention except in so far as specifically pointed out in the appended claims.

55 I claim as my invention:—

1. A separator of the character described, having two upright side sections laterally spaced apart and provided between their ends with notches to receive one or more cross strips, and each side section being provided at each end thereof with an integral portion adapted to be bent into a position substantially at right-angles to the body of the section and having an integral flap cut from the body of the section and adapted

to project from that side of said section opposite to the side from which said integral portion extends, the lower edges of said flaps and integral portions being in the same plane with the lower edges of said side sections.

2. A separator of the character described, comprising two upright side sections laterally spaced apart and provided between their ends with notches to receive one or more cross strips; and a transverse section connected with said side sections and extending between the same at one end of the separator, and each side section being provided at each end thereof with a tongue cut from the body of the section and adapted to project outward therefrom substantially at right-angles to the body of the section, and the lower edges of said tongues being in the same plane with the lower edges of said side sections.

3. A separator of the character described, made from a strip of sheet material and bent along fold lines into a position having two upright side sections laterally spaced apart, and a transverse section extending between said side sections at one end of the separator, said side sections being provided at the ends thereof with integral tongues cut from the body of the side sections and adapted to be bent into positions projecting outward therefrom at the corners of the separator.

4. A separator of the character described, made from a strip of sheet material and bent along fold lines into a position having two upright side sections laterally spaced apart, and a transverse section extending between said side sections at one end of the separator, said side sections being provided at the ends thereof with integral tongues cut from the body of the side sections and adapted to be bent into positions extending outward therefrom at the corners of the separator, each side section being provided at the end thereof opposite said transverse section with an integral wing adapted to be bent to extend inward from the side sections, and the lower edges of said tongues and wings being in the same plane with the lower edges of said side sections.

5. A blank for a separator of the character described, comprising a flat strip of sheet material having transversely arranged notches opening outward through one of the longitudinal edges of said strip, the latter being divided into two end sections and an intermediate section by a score or fold line at each end of the intermediate section and extending transversely partially across the strip from the longitudinal edge thereof through which said notches open, said strip being provided adjacent each end thereof with a score or fold line extending trans-

versely partially across the strip from said last named longitudinal edge thereof and having a tongue cut in the body of the strip at each of said several fold or score lines.

5 In testimony that I claim the foregoing as my invention, I affix my signature in the

presence of two witnesses, this 31st day of August, A. D. 1916.

HERBERT T. FOGG.
